(57) **CLAIM**

We claim the ornamental design for a cosmetic brush, as
shown and described.

DESCRIPTION

FIG. 1 is a top isometric view of a first embodiment of a
cosmetic brush.

FIG. 2 is an enlarged top isometric view of a portion of the
cosmetic brush of FIG. 1.

FIG. 3 is a front elevation view of the cosmetic brush of FIG.
1, the rear elevation view is a mirror image of the front
elevation view.

FIG. 4 is an enlarged front elevation view of a portion of the
cosmetic brush of FIG. 3.

FIG. 5 is a top plan view of the cosmetic brush of FIG. 1.

FIG. 6 is a bottom plan view of the cosmetic brush of FIG. 1.

FIG. 7 is a right-side elevation view of the cosmetic brush of
FIG. 1, the left-side elevation view is a mirror image of the
right-side elevation view.

FIG. 8 is an enlarged right-side elevation view of a portion of
the cosmetic brush of FIG. 1.

FIG. 9 is a top isometric view of a second embodiment of a
cosmetic brush.

FIG. 10 is a front elevation view of the cosmetic brush of FIG.
9, the rear elevation view is a mirror image of the front
elevation view.

FIG. 11 is an enlarged front elevation view of a portion of the
cosmetic brush of FIG. 10.

FIG. 12 is a top plan view of the cosmetic brush of FIG. 9.

FIG. 13 is a bottom plan view of the cosmetic brush of FIG. 9.

FIG. 14 is a right-side elevation view of the cosmetic brush of
FIG. 9, the left-side elevation view is a mirror image of the
right-side elevation view; and,

FIG. 15 is an enlarged right-side elevation view of a portion of
the cosmetic brush of FIG. 9.

The broken lines showing a handle illustrate a portion of the
cosmetic brush that forms no part of the claimed design.

1 Claim, 8 Drawing Sheets
